ABSTRACT OF THE DISCLOSURE

Quaternary lower alkoxy(lower)alkyl-1,2,4-oxadiazolyl-pyridinium salts are described along with methods of preparing the same. These compounds show hypoglycemic activity evidenced by their ability to lower blood sugar levels.

The present application is a continuation-in-part of our application Ser. No. 676,706 filed Oct. 20, 1967, now abandoned.

PRIOR ART

Applicants are aware of British Pat. 875,887 directed to pyridinium salts. However the present invention is directed to subject matter and utility not disclosed therein.

SUMMARY OF THE INVENTION

This invention relates to new quaternary lower alkoxy(lower)alkyl-1,2,4-oxadiazolylpyridinium salts which may be illustrated by the following formula:

wherein R is lower alkyl, R₁ is lower alkoxy(lower)alkyl, X is a pharmaceutically acceptable anion and Z is a trivalent radical selected from the group consisting of

and

The dotted line represents one double bond, the position of which is dependent upon the definition of Z. When Z is

the double bond is between the N and carbon containing R, and when Z has the other meaning, the double bond is in the other position. The terms lower alkyl and lower alkoxy include those radicals having 1 to 4 carbon atoms.

In general, the compounds are crystalline solids, soluble in water.

The compounds of the present invention may be prepared by reaction of a 1,2,4-oxadiazolylpyridine with a lower alkoxy(lower)alkyl halide at a temperature of 0° to 200° C. with or without a solvent, such as a lower alkyl alcohol, for a time of one minute to twenty-four hours in an open vessel or a sealed bomb.

The reaction is illustrated schematically below:

2

wherein R, R₁, Z and X are as hereinbefore defined.

Among the quaternary compounds of the present invention are, for example: 1-(2-ethoxyethyl)-4-(5-methyl-1,2,4-oxadiazol-3-yl)pyridinium chloride, 1-(2-methoxyethyl)-4-(5-methyl-1,2,4-oxadiazol-3-yl)pyridinium chloride, 1-(2-propoxyethyl)-4-(5-methyl-1,2,4-oxadiazol-3-yl)pyridinium bromide, 1-(2-ethoxymethyl)-4-(5-methyl-1,2,4-oxadiazol-3-yl)pyridinium iodide, 1-(2-propoxymethyl)-4-(5-methyl-1,2,4-oxadiazol-3-yl)pyridinium chloride.

The quaternary compounds of the present invention show hypoglycemic activity which indicates they are useful as medicaments in the lowering of blood sugar levels. When the quaternary compounds are administered orally to normal mice, a reduction of blood sugar levels is observed. The compounds of this invention are administered by gavage as saline solutions to CF-1 mice (Carworth Farms, 18-25 grams (4-6 animals). Control animals receive an equivalent volume of saline. Food is withheld from animals after dosing. Blood glucose is determined on 0.05 ml. samples of blood by the method of Hoffman [J. Biol. Chem., 120, 51 (1937)] as adapted to the Technicon AutoAnalyzer® and is expressed as percent change from predose values. The data are shown in the table hereinafter. These results show that the compounds of the present invention are useful in lowering the blood glucose concentrations of warm-blooded animals.

TABLE

30	Decrease in blood glucose in normal mice after oral administration of 1,2,4-oxadiazolylpyridinium salts
	Compound—1 - (2 - ethoxyethyl)-4-(5-methyl-1,2,4-oxadiazol-3-yl)pyridinium chloride:
35	Dose, mmoles/kg. ----- 3.0
	Hours after dosing ----- 3
	Percent decrease in blood glucose ----- 27±4

The products of the present invention as hypoglycemic agents can be incorporated in various pharmaceutical forms such as tablets, capsules, pills and so forth, for immediate or sustained release, by combining with suitable carriers. They may be in the form of dosage units for a single therapeutic dose or in small units for multiple dosages or in larger units for division into single doses. Obviously, in addition to the therapeutic hypoglycemic compounds, there may be present excipients, binders, fillers and other therapeutically inert ingredients necessary in the formulation of the desired pharmaceutical preparation.

DETAILED DESCRIPTION

The following examples describe in detail the preparation of representative quaternary lower alkoxy(lower)alkyl 1,2,4-oxadiazolylpyridinium salts of this invention.

EXAMPLE 1

Preparation of 4-(5-methyl-1,2,4-oxadiazol-3-yl)pyridine

A mixture of 27 g. of isonicotinamidoxime and 50 ml. of acetic anhydride is warmed on a steam bath for 2 hours, and then heated under reflux for 3 hours. The solvent is distilled and the dark liquid residue is diluted with water. The crystals which form are collected, washed with water, and recrystallized from ethanol to provide colorless crystals, melting point 92-93° C.

EXAMPLE 2

Preparation of 1-(2-ethoxyethyl)-4-(5-methyl-1,2,4-oxadiazol-3-yl)pyridinium chloride

A mixture of 5.0 g. of 4-(5-methyl-1,2,4-oxadiazol-3-yl)pyridine and 15 ml. of 2-chloroethyl ethyl ether is heated in a bomb at 130° C. for 20 hours. The excess 2-chloroethyl ether is evaporated and the black residue

3

is recrystallized from isopropyl alcohol-ether to give off-white crystals, melting point 187-188° C.

EXAMPLE 3

Preparation of 4-(5-ethyl-1,2,4-oxadiazol-3-yl)pyridine

A mixture of 27 g. of isonicotinamidoxime and 60 ml. of propionic anhydride is warmed on a steam bath for 2 hours and then heated at 145° C. for 4 hours. The solvent is distilled and the dark liquid residue is diluted with water. The crystals which form are collected, washed with water, and recrystallized from petroleum ether to provide colorless crystals, melting point 42-44° C.

EXAMPLE 4

Preparation of 1-(3-propoxypyropyl)-4-(5-ethyl-1,2,4-oxadiazol-3-yl)pyridinium chloride

A mixture of 5.0 g. of 4-(5-ethyl-1,2,4-oxadiazol-3-yl)pyridine and 15 ml. of 3-chloropropyl propyl ether is heated in a bomb at 130° C. for 20 hours. The excess 3-chloropropyl ether is evaporated and the residue is recrystallized to give the product of the example.

We claim:

1. A quaternary oxadiazolylpyridinium salt of the formula:

4

wherein R is lower alkyl, R1 is lower alkoxy(lower)alkyl, X is a pharmaceutically acceptable anion, Z is a trivalent radical selected from the group consisting of

5 and

10 and the dotted line represents one double bond, the position being dependent upon the definition of Z.

2. A quaternary oxadiazolylpyridinium salt according to claim 1: 1-(2-ethoxy(lower)alkyl-4-(5-methyl-1,2,4-oxadiazol-3-yl)pyridinium chloride.

3. The quaternary oxadiazolylpyridinium salt according to claim 1: 1-(2-ethoxyethyl)-4-(5-methyl-1,2,4-oxadiazol-3-yl)pyridinium chloride.

4. The quaternary oxadiazolylpyridinium salt according to claim 1: 1-(3-propoxypyropyl)-4-(5-ethyl-1,2,4-oxadiazol-3-yl)pyridinium chloride.
